DENTAL CASTING APPARATUS

George A. Yantis, Elma, Wash.

Application June 16, 1939, Serial No. 279,425

7 Claims. (Cl. 22—69.1)

This invention relates to mechanism for casting metals in investment material. More particularly, this invention relates to mechanism for dental castings, as inlays, crowns, and partial dentals, etc.

Heretofore great difficulty has been experienced in the production of accurate dental castings. A perfect impression in wax of the cavity in a tooth may be obtained, but because of inaccuracies in the casting process, difficulty has been obtained in reproducing a casting which will properly fit within the cavity in the tooth. One of the difficulties heretofore encountered has been in obtaining the proper temperature and fluidity of the gold at the time of casting.

My invention provides means which are controlled by the fluid condition of the melted gold (herein referred to as gold, although, of course, alloying metals are included to provide the proper degree of hardness and wearing qualities) to determine the exact period at which the melted gold is to be delivered to the casting investment. While heretofore it has been recognized that the fluid condition of the gold is important in determining the proper time of casting, no practical, simple and efficient means have been produced which will take advantage of this principle. For example, the patent issued to M. F. Patterson, Dental Supply Co. No. 1,767,023, issued June 24, 1930, attempts to use electrodes, electrical contact between which is carried by the melted gold. The establishing of electrical communication between the electrodes is used to control the operation of a centrifugal casting machine.

Such type of apparatus has proven impractical as the electrodes must be placed in the melting chamber and will attain impractical temperatures for the electrodes. For example, the electrodes will attain temperatures which will cause the electrodes to alloy out and become a part of the casting material. Any arcing between the electrodes will cause an oxidation of the gold. The electrodes must be spaced apart such relatively short distances because of the small amount of melted gold present so that serious problems are involved in maintaining the electrodes.

In my invention I employ a tiltably mounted gold melting crucible, the floor of which is inclined relative to the horizontal. The gold to be melted is placed on a higher portion of the inclined floor member and when the gold becomes melted so it will flow down the inclined floor member, the gold serves to tilt the crucible. At this point the gold is at the proper fluidity for casting and I employ means which are controlled by the

tilting of the tilttable crucible to cause the melted gold to be delivered from the crucible to a casting investment.

In melting metals for casting it has been found that it is important to melt the gold and raise its temperature a little above the melting point before casting but not overheat it. If we are able to cast at a certain critical temperature, as above described, we will greatly increase the strength and ductility of the casting, and eliminate weakening pits and porous areas. This invention makes it possible to do this automatically and insure uniform, predictable results with every casting.

In my invention the fluid condition of the gold is the determining feature in the control mechanism for delivering the gold from the crucible to the casting investment. Also in my invention the temperature of the casting investment is maintained (by the use of a rheostat, if necessary) at the temperature to receive the melted gold. This invention is in the nature of an improvement on my co-pending application Serial No. 204,617, allowed February 8, 1939, Patent No. 2,171,778.

Thus, I am able in my invention to bring the melted gold to a certain critical temperature at the time of casting and at the same time to hold the temperature of the investment at a certain predetermined temperature while casting and do it all automatically without help from the operator of the machine after it is once turned on.

The above mentioned general objects of my invention, together with others inherent in the same, are attained by the mechanism illustrated in the following drawings, the same being preferred exemplary forms of embodiment of my invention, throughout which drawings like reference numerals indicate like parts:

Figure 1 is a view partly in elevation and partly in section of casting apparatus constructed in accordance with this invention, electrical devices connected therewith being diagrammatically shown;

Fig. 2 is a fragmentary cross sectional view of the same taken substantially on broken line 2—2 of Figure 1, parts being shown in elevation;

Fig. 3 is a fragmentary enlarged cross section taken substantially on broken line 3—3 of Fig. 2;

Fig. 4 is a detached plan view, with parts broken away, of the solenoid operated trip device shown by dotted lines in Figure 1;

Fig. 5 is a detached plan view of a switch mechanism shown in Figure 1;

Fig. 6 is a view partly in elevation and partly in section of another casting apparatus constructed in accordance with this invention, parts being

broken away and electrical devices connected therewith being diagrammatically shown;

Fig. 7 is a fragmentary enlarged sectional view taken substantially on broken line 7—7 of Fig. 6;

5 Fig. 8 is a view partly in section and partly in elevation and partly broken away of still another casting apparatus constructed in accordance with my invention, electrical devices connected therewith being diagrammatically shown;

10 Fig. 9 is a detached plan view of the crucible employed in the apparatus shown in Fig. 1; and

Fig. 10 is a sectional view of said crucible on broken lines 10—10 of Fig. 9.

Figs. 1 to 5 show an embodiment of this invention in which a tiltably mounted crucible is disposed within a swingingly mounted crucible housing and a casting furnace is removably secured to the crucible housing and swings with the crucible housing. In this construction the crucible 15 and casting furnace are supported substantially horizontally while the metal is being melted and the casting or pouring of the metal, after it is melted, is accomplished by swinging the crucible housing and casting furnace downwardly 25 into a position in which the crucible housing is above the casting furnace so that the molten metal will be delivered into investment means in the casting furnace.

Figs. 1 to 5 show a crucible housing 15 having 30 a crucible chamber 14 therein. The crucible housing 15 has a transverse tube 16 embedded therein near one end. The tube 16 is pivotally mounted on a horizontal tubular bearing member 17 that is supported by an upright panel 18 in an upright support 19. The tubular bearing member 17 also serves as a conduit for air or gas under pressure which is delivered thereto through conduit means 20 (Fig. 2) having a control valve 21 therein. The crucible housing 15 has a lining 22 therein within which is provided the chamber 14 for the reception of a crucible 23. The lining 22 has electric heating means 24 embedded therein. The preferred form of the crucible 23 is also shown in Figs. 9 and 10.

45 A casting furnace 25 is releasably and removably connected with the crucible housing 15 in end to end relation. Preferably a releasable hinge means 26 and a releasable securing means 27 are used to connect the casting furnace 25 with the crucible housing 15. The casting furnace 25 has a lining 28 of refractory material within which is provided a heating chamber 29 for the reception of an investment ring 30 having investment material 31 therein. Electric heating means 29' is provided in connection with the heating chamber 29.

50 A pyrometer 32 is provided in the casting furnace to accurately record the temperature of the casting investment material 31. A rheostat can be provided to hold the temperature of the investment at a predetermined temperature until ready for the casting operation to take place. The remaining structure of the casting furnace 25 is shown and described in detail in my said co-pending application.

55 The crucible 23 is preferably formed of heat resistant non-metallic material, such as porcelain. This crucible 23 is pivotally supported within the chamber 14 on a fulcrum member 33. A hook shaped member 34 on the bottom portion of the crucible 23 engages with the upper hook shaped end portion of the fulcrum member 33 and helps prevent displacement of the crucible 23. The forward portion of the crucible is preferably inclined to facilitate pouring of molten

metal therefrom and said inclined portion is positioned at the mouth of the chamber 14. A crucible positioning means in the form of a shoulder 35 in the crucible housing is provided for the rear end portion of the crucible to rest on when the parts are in the position shown in Fig. 1. The crucible floor member 36 on which the metal to be cast is melted is inclined, relative to the horizontal, downwardly from the rear toward the front end of the crucible when the crucible is supported in the metal melting position shown in Fig. 1. This incline of the crucible floor member 36 may be attained in different ways, provided that said floor portion 36 is always inclined sufficiently, when the crucible is in a metal melting position, so that when metal is placed on a higher portion of said floor member and melted it will flow by gravity to a lower portion of said floor member. The shifting of weight that occurs in the crucible when the metal melts and flows to the lower portion of the crucible is sufficient to tilt the crucible on the fulcrum member 33 and this tilting of the crucible is used to actuate electrical devices which control the pouring or casting of the melted metal.

25 The distribution of the weight of the crucible and the balance of the crucible on its fulcrum are such as to insure the tilting of said crucible from the initial or metal melting position, shown by full lines in Fig. 1, to a second position shown 30 by dot and dash lines in Fig. 1, when the smallest amount of metal that will ordinarily be used becomes liquid and flows along floor member 36 from a higher to a lower portion of the crucible. The second position into which the crucible will 35 be moved, shown by dot and dash lines in Fig. 1, is a switch operating position which controls the casting of the melted metal. Controlling the casting or pouring of the metal by the flow of the metal from one part to another of the crucible 40 insures that the metal will have to be fully and completely melted and in proper condition for casting before the actual casting or pouring can take place.

45 Preferably the floor member 36 is provided with a restricted passageway formed between walls 36' (see Figs. 9 and 10). This passageway serves to restrict the flow of the metal until it is all fluid.

A pyrometer member 37 may be provided in the crucible housing to give an accurate reading 50 of the temperature within the crucible chamber 14.

The housings 15 and 25 are spaced outwardly from the panel 18, as best shown in Fig. 2, so that they will swing clear of certain electrical 55 control devices on said panel.

The electrical control means controlled by the tilting of the crucible 23 comprises a switch lever 38 fulcrumed on a pivot 38'. One end of switch lever 38 is positioned to be engaged by a portion 60 of the crucible 23, as shown in Fig. 1, so that the switch lever 38 will be angularly moved by movement of the crucible produced by the melting and flowing of the metal within said crucible. The other end portion of switch lever 38 carries a contact member 39 positioned to electrically contact another contact member 40 when the switch lever 38 is angularly moved by upward movement of the portion of the crucible 23 which engages therewith. The switch lever 38 is arranged, as 70 by balance of weight, so that it will maintain the switch comprising contacts 39—40 open except when said lever 38 is moved into a closed switch position by crucible 23.

Two circuit wires 41 connect the contact 75

members 39 and 40 with a retarded relay 42 in such a manner that the retarded relay 42 will be energized by the closing of the switch comprising contact members 39 and 40. Circuit wires 41 may be connected with any suitable source of energy, not shown. Also a control switch capable of either manual or automatic operation is preferably interposed in circuit wires 41 as hereinafter described. Switch lever 38 and contacts 39 and 40 may be operatively disposed in a passageway 43 provided in the wall and lining of crucible housing 15 and extending from the crucible chamber 14 to tubes 16 and 17, as hereinafter described.

15 The retarded relay 42 controls the opening and closing of a switch 44 that is connected in circuit with a solenoid 45 by circuit wires 46 which extend to any suitable source of energy, not shown. The solenoid 45, Figs. 1 and 4, has 20 a plunger 47 that is connected by a pivot 48 with one arm of a bell crank lever 49. The other arm of the bell crank lever 49 is movable into and out of a supporting position relative to a lug 50 on the crucible housing 15. The bell crank lever 49 is mounted on a pivot 51 that is supported by a bracket 52 from a panel 18. The bell crank lever 49, when positioned under the lug member 50, is adapted to support the housing parts in the horizontal position shown in 25 Fig. 1.

30 The control means for the heating element 24 in the crucible housing and the heating element 29' in the casting furnace are preferably as follows: Electrical conductors 53 from a suitable source of energy, not shown, are connected with the heating element 24. Two switches 54 and 55 are interposed in the conductors 53 in circuit with the heating element 24. Similarly electrical conductors 56 connect heating element 29' of the casting furnace with a source of energy, not shown, and two switches 57 and 58 are interposed in the conductors 56 in circuit with heating element 29'. The two switches 54 and 57, diagrammatically shown in Fig. 1, are manually controlled switches of well known form capable of providing electrical connections for "high," "low" and "medium" heat and having "off" or open switch positions. The two switches 55 and 58 are capable of being operated both 35 manually and by the swinging movement of the casting apparatus housings 15 and 25. Another switch 59 similar to switches 55 and 58 is preferably interposed in conductors 41 which control the supply of current to the retarded relay 42.

40 The switch 55 is more fully shown in Fig. 5. The switches 53 and 59 are similar to the switch 55 and the showing and description of the switch 55 will apply equally well to the switches 58 and 59. The switch 55, Fig. 5, comprises a fixed contact member 61 and a movable contact member 62 mounted on a pivot 63 and pivotally movable into open or closed switch position relative to the fixed contact member 62. When 45 contact member 62 is in the position shown by full lines in Fig. 5, the electrical circuit through contact members 61-62 will be closed and the heating element 24 may be energized. Also for this position of contact member 62, the insulated end portion 64 of the contact member 62 is positioned in the path of movement of the lug 50 on the crucible housing 15, whereby it will be engaged by said lug 50 as the two housing members 15 and 25 swing downwardly and moved thereby into the open switch position shown by 55 dotted lines in Fig. 5. This breaks the circuit

to the heating coil 24 when the housing members 15 and 25 swing downwardly into the metal casting or pouring position. Also the contact member 62-64 may be manually moved into the open switch position shown by dotted lines 5 in Fig. 5, regardless of the position of the housings 15 and 25.

60 The contact member 62-64 may be moved manually to a closed switch position shown by dot and dash lines in Fig. 5, in which closed 10 switch position it is out of the path of the lug 50 so that the circuit to electric heater 24 may be maintained closed regardless of the position of housing members 15 and 25.

65 Similarly the switches 58 and 59 will serve to 15 electrically connect or disconnect the heating element 29' and the retarded relay 42 from their respective circuits. The lugs 65 and 66 carried by housing member 25, shown by dotted lines in Fig. 1, function similarly as respects switches 20 58 and 59 as lug 50 functions as respects switch 55.

70 Pyrometer members 32 and 37 may be connected with a common indicator 67 through a selectively operable switch means 68 which will 25 cause them to respectively operate said indicator 67.

75 In the operation of the device shown in Figs. 1 to 5, inclusive, the metal 60 to be melted and cast is placed on a higher portion of the crucible floor member 36. The said crucible is properly positioned within the crucible housing 15 and the crucible housing 15 and casting furnace 25 are supported by bell crank 49 in substantially 30 a horizontal position as shown in Fig. 1. Tilting of the crucible 23, due to the melting and flowing of the gold therein, will close the switch comprising contacts 39 and 40 and supply energy to retarded relay 42. The energizing of the retarded relay 42 will close the circuit to the 40 solenoid 45 and move the bell crank 49 into the releasing position shown by dot and dash lines in Fig. 4. This will release the crucible housing and permit said crucible housing 45 and the casting furnace to swing downwardly by gravity and come to rest in a substantially vertical position. As the crucible housing and casting furnace swing downwardly the molten gold in the crucible will be poured or cast into a suitable cavity in the investment material. 50 The retarded relay 42 is capable of being set so that the closing of the switch 44 will be delayed for a predetermined period of time after the retarded relay 42 is energized. Also the restricted passage between walls 36' serve to 55 restrict the metal until the same is all melted. These provide for delaying the pouring of the molten metal for a predetermined time after it has become sufficiently liquefied to flow from one portion of the crucible to another and insures 60 that all of the gold will be completely melted and in a proper condition for casting before the casting operation takes place.

65 The tubular members 16 and 17, upon which housing 15 is mounted for swinging movement, have ports 70 and 71, see Figs. 1 and 3, which serve as means for automatically controlling the inlet of gas under pressure to the crucible chamber 14. This gas under pressure passes through 70 registering ports 70 and 71 and functions to force the melted metal into the cavity in the investment material in casting. When the housing members 15 and 25 are in the horizontal position, the ports 70 and 71 are out of registration and when the housing members 15 and 25 are 75

- in a vertical position, the ports 70 and 71 are in registration.
- Further description of the mode of operation of the devices shown in Figs. 1 to 5, inclusive, and particularly as to parts not herein claimed, may be found in my said copending application.
- Fig. 6 shows this invention adapted to casting apparatus in which a crucible unit is movable in a circular path around a center and is adapted to be selectively positioned to deliver melted metal into investment means in any one of a plurality of non-movable casting furnaces positioned at equal radial distances from the center about which the crucible unit moves.
- Much of the apparatus shown in Fig. 6 is similar to that disclosed in my said copending patent application, to which reference is made for a complete description of mechanism shown in said Fig. 6, but not herein described in detail.
- The casting furnaces shown in Fig. 6 are similar in construction to the casting furnace shown in Figs. 1 to 5, but are fixedly mounted, whereas the casting furnace shown in Figs. 1 to 5 is swingly mounted.
- The crucible of Fig. 6 and the operating mechanism connected therewith differs from that shown in Fig. 5 principally, in that the crucible is movable into and out of registration with a fixedly supported casting furnace.
- Fig. 6 discloses a base 72 having a fixed upright tubular post 73 thereon. A plurality of casting furnaces 25 are mounted on the base 72 preferably with their axes at equal radial distances from the post 73. Each casting furnace 25 has a chamber 29, heated by an electric heater 29' and adapted to receive an investment ring 30 with investment material 31 therein. Also each casting furnace has a pyrometer 74 connected with an indicator 75 through conductors 76 and selective contact mechanism 77. Another conductor 76' connects a pyrometer 74 in a crucible housing 78 with the indicator 75 through the selective contact mechanism 77. Manually operated switches 79 control suitable heating circuits to heating elements 29' of the casting furnaces and to a heating element 80 in the crucible housing 78. These switches preferably each provide for three speeds of heat and each have an open circuit position.
- The crucible housing 78 shown in Fig. 6 has a lining 81 provided with a crucible chamber 82 having the heating element 80 in the wall thereof. A crucible 83 is supported within the chamber 82 by a fulcrum member 84 and hook shaped member 85. The crucible 82 has three positions, first, a melting position shown by full lines in Fig. 6, in which it is supported with the floor member 86 thereof at sufficient incline to the horizontal to insure that gold placed on a higher portion thereof will flow down said inclined floor member to a lower portion thereof, second, an inclined position, shown by broken lines in Fig. 6, into which it is moved by the melted gold flowing on said inclined floor member from a higher portion thereof, and third, a dumping position, shown by dot and dash lines in Fig. 6, in which said crucible is approximately upright and delivers melted gold to a casting investment.
- The means, controlled by the movement of the crucible from its said first position to its second position, for controlling the movement of the crucible into its discharging position comprises a thrust rod 87 guided for vertical movement in a passageway 88 in the crucible housing 78. Ribs 89 are provided on rod 87, see Fig. 7, to leave space around rod 87 for gas under pressure to flow through passageway 88 into chamber 82. The lower end portions of the ribs 89 are adapted to engage with a shoulder 90 to limit downward movement of rod 87. The lower end of rod 89 is positioned in close proximity to the upper edge of the crucible 83 when said crucible is in the metal melting position shown by full lines in Fig. 6.
- The upper end portion of rod 89 is positioned to engage with a resilient switch member 91 and move said switch member 91 into contact with another resilient switch member 92. Switch members 91 and 92 control a circuit through conductors 93 to a retarded relay 94. The retarded relay 94 operates a switch 95 which controls a circuit through conductors 96 to a solenoid 97. The solenoid 97 has a core member 98, provided with a valve 99 that is operable as respects a valve seat 100. Also core member 98 is preferably connected with switch member 92.
- A gas tight housing 101 encloses the solenoid 97 and has a gas tight connection with the top end portion of the crucible housing 78. Also the chamber 102 in which the core member 98 operates is gas tight and the upper end portion of said chamber 102 is connected with a gas inlet conduit 103. Conduit 103 has a valve 104 and is connected with a flexible conduit 105. The flexible conduit 105 preferably extends downwardly through the tubular post 73 into the base 72 where it may connect with any suitable source of supply of gas under pressure, not shown. Also all of the circuit wires and conductors from the crucible unit preferably extend downwardly through post 72.
- The crucible housing 78 is supported from the post 72 by a two part arm means 106 which is angularly and vertically adjustable on the post 72 and which permits the crucible housing 78 to be angularly moved on an axis perpendicular to the post 72. This provides for moving the crucible housing 78 into and out of proper registration and operative engagement with the several casting furnaces 25 and for angularly moving the crucible housing 78 about the axis of the arm means 106 to facilitate insertion and removal of the crucible and the material to be melted therein.
- In the operation of the casting apparatus shown in Fig. 6, metal 60 to be melted is placed on a higher portion of the floor member 86 of the crucible 83 and said crucible is supported in the melting position shown by full lines in Fig. 6. When the metal 60 becomes liquid it will flow to a lower portion of the crucible, and in so doing, will shift the weight in the crucible and tilt the same into the second position, which is the switch closing position shown by broken lines in Fig. 6. This will move rod 87 upwardly and close the circuit through resilient switch members 91 and 92 to retard relay 94. However the weight of the solenoid core member 98 resting on switch member 92 will arrest the movement of the crucible 83 at this point and hold the same in the said second position, shown by broken lines, and the metal will not be cast or poured until after the retarded relay 94 operates. Retarded relays 94 and 42 may not be necessary but are shown in case they are needed. The delay thus provided may be long enough to insure that all of the metal has had time to become properly melted and to flow to the lower portion of the crucible. Thereafter, and at the end of the predetermined time, the retarded relay 94 will close the switch 95, en-

5 energize the solenoid 97, and lift the core member 98. When core member 98 is lifted, the weight of the crucible 83 and melted metal therein will further lift the rod 87 and free the crucible 83 and the crucible will tilt downwardly into a position as shown by dot and dash lines in Fig. 6 and discharge the melted metal onto the investment material. The lifting of the core member 98 will open the valve 99 simultaneously with the pouring 10 of the metal and this will admit gas under pressure to force the melted metal into a cavity in the investment material.

15 The casting apparatus shown in Fig. 8 comprises a crucible housing 107, having a lining 108 provided with heating element means 109 and forming a crucible chamber 110. A crucible 111 is pivotally supported within chamber 110 by fulcrum means 112 and hook like means 113. The crucible 111 has three operative positions, first, a 20 metal melting position shown by full lines, second, a switch closing position shown by broken lines, and third, a metal pouring position shown by dot and dash lines.

25 A casting furnace 114 having an investment ring 115 and investment material 116 therein cooperates with crucible housing 107 to receive melted metal from crucible 111.

30 A bell crank lever 117 pivoted on pivot means 118 has one arm thereof positioned to be engaged by the crucible 111 and the other arm thereof extending upwardly through a slot 119 in the upper portion of the crucible housing 107.

35 A housing 120 is mounted on the upper end portion of crucible housing 107 and the upper end portion of bell crank lever 117 extends into this housing 120. A resilient contact member 121 has one end portion movable into and out of the path of movement of the upper end portion of the bell crank lever 117. The resilient contact member 121 is connected with a plunger 122 of a solenoid 123, thus resilient contact member 121 is moved vertically with plunger 122 into and out of the path of the upper end portion of bell crank arm 117. When bell crank arm 117 engages with resilient contact member 121 it moves said contact member 121 into contact with a fixed contact member 123, which is out of the path of movement of bell crank arm 117. This closes a circuit through conductors 124 to a retarded relay 125. The retarded relay 125 controls a switch 126 that is connected in the circuit wires 127 of the solenoid 123. This provides for first energizing the retarded relay 125 in response to movement of the bell crank lever 117 and then after a predetermined time delay, energizing the solenoid 123.

50 A conduit 128 for gas under pressure communicates with the crucible chamber 110. A valve 129 in conduit 128 is connected by a lever 130 with solenoid plunger 122 so that said valve will be operated in one direction by movement of the plunger 122. A spring 131 may be provided to operate the valve 129 in the other direction.

55 Two separate switch members 132 and 133 are connected with the lever 130 and movable thereby into and out of electrical contact with other switch members 134 and 135 respectively. The switch members 132, 133, 134 and 135 form two switches that are connected by conductor means 136 and 137 respectively with the heating element 109 in the crucible housing and with a heating element 138 in the casting furnace 114 and are connected with any suitable source of energy (not shown).

60 In the operation of the device shown in Fig. 8, metal 60 to be melted is placed on a higher por-

65 tion of the floor member of the crucible 111 and said crucible 111 is supported in the melting position shown by full lines in Fig. 8. In this position the upper rear edge of the crucible is positioned below an arm of bell crank lever 117. When the metal 60 becomes liquid it will flow to a lower portion of the crucible and in so doing will shift the weight in the crucible and tilt the crucible into the second position, which is the position shown by broken lines in Fig. 8. In this 10 second position the upper end portion of bell crank lever 117 will engage with the resilient contact member 121 and move the same into electrical contact with contact member 123. As the resilient contact member 121 is positioned in the 15 path of movement of the bell crank lever 117 the fixed contact member 123 will prevent movement of the portion of spring contact member 121 and in turn serve as a stop for the bell crank lever 117. In this position the bell crank lever 117 20 will hold the crucible 111 in the said second position until after the retarded relay 125 has operated to energize the solenoid 123 and move the plunger 122 and the resilient contact member 121 upwardly. Release of bell crank lever 117 upon 25 upward movement of resilient contact 121 releases the crucible 111 and allows the same to tilt to the third position, which is the metal discharging position shown by dot and dash lines in Fig. 8. In this latter position metal will be discharged 30 from the crucible 111 onto the investment 116 in the casting furnace 114. In view of the fact that the other two modifications of this invention show in detail casting furnaces, the casting furnace in Fig. 8 has been broken away. Simultaneously 35 with the pouring of the melted metal the valve 129 in the conduit 128 is moved to an open position and admits gas under pressure to force the melted metal into a cavity in the investment material 116. Also at this same time and in response to upward movement of plunger 122, the switches controlling the circuits to heating elements 109 and 139 are opened, thus deenergizing said elements.

40 In the various forms of this invention I have provided a tiltable gold melting crucible. An inclined floor member is carried by this crucible. The gold to be melted is placed on a higher portion of the inclined floor member. As the gold becomes melted it will flow down the inclined 50 floor member and cause the tiltably mounted crucible to assume a second position. Upon the tiltably mounted crucible assuming its second position, electric switch means are energized. These electric switch means are positioned in a 55 control circuit to control the delivery of the gold to a casting furnace. Preferably a retarded relay to provide time delay is used so that the gold will be fully melted and in the proper fluid condition before it is delivered from the crucible 60 into the casting furnace. Upon the delivery of the gold into the casting furnace, gas is introduced under pressure to force the gold into a cavity in investment means in the casting furnace. 65

70 Obviously, changes may be made in the forms, dimensions and arrangement of the parts of my invention, without departing from the principle thereof, the above setting forth only preferred forms of embodiment.

75 I claim:

1. In a device of the class described, a pivotally mounted housing; a tiltably mounted crucible in said housing; an inclined floor member carried by said crucible and on which gold 75

- to be melted may be placed; means mounting said crucible for movement between a first position in which gold to be melted is supported on a higher portion of said inclined floor member and 5 a second position into which the crucible is moved by flowing of the melted gold down said inclined floor member; casting investment means carried by said pivotally mounted housing in a receiving position as respects said crucible when said housing is pivotally moved; and means controlled by the movement of said crucible for pivotally moving said housing and delivering melted gold from said crucible into said casting investment.
2. In a device of the class described, a housing member; a casting investment in said housing member; a movably mounted crucible in said housing member provided with an inclined floor member and operatively positioned relative to said casting investment to move to a gold discharging position as respects said casting investment; crucible mounting means movably mounting said crucible to provide two gold melting and retaining positions and a gold discharging position, a first gold melting and retaining position 20 in which gold to be melted is supported on a higher portion of said inclined floor member, a second gold melting and retaining position into which the crucible is moved by the flowing of melted gold down said inclined floor member, and a gold discharging position in which gold may be discharged into said casting investment; and crucible gold discharging means controlled by the movement of said crucible to its said second gold melting and retaining position for delivering melted gold from said crucible to said casting investment.
3. In a device of the class described, a housing member; a casting investment in said housing member; a movably mounted crucible in said housing member provided with an inclined floor member and operatively positioned relative to said casting investment to move to a gold discharging position as respects said casting investment; crucible mounting means movably mounting said crucible to provide two gold melting and retaining positions and a gold discharging position, a first gold melting and retaining position in which gold to be melted is supported on a higher portion of said inclined floor member, a second gold melting and retaining position into which the crucible is moved by the flowing of melted gold down said inclined floor member, and a gold discharging position in which gold may be discharged into said casting investment; means forming a restricted passageway on said inclined floor member positioned in the path of flow of the melted gold and limiting the movement of the gold until it is fully melted; and crucible gold discharging means controlled by the movement of said crucible to its said second gold melting and retaining position for delivering melted gold from said crucible to said casting investment.
4. In a device of the class described, a housing member; a casting investment in said housing member; a movably mounted crucible in said housing member provided with an inclined floor member and operatively positioned relative to said casting investment to move to a gold discharging position as respects said casting investment; crucible mounting means movably mounting said crucible to provide three positions, a first gold melting and retaining position in which gold to be melted is supported on a higher portion of said inclined floor member, a second gold melting and retaining position into which

the crucible is moved by the flowing of melted gold down said inclined floor member, and a gold discharging position in which the crucible is moved by gravity when released; and crucible releasing means controlled by the movement of said crucible to its said second gold melting and retaining position for releasing said crucible and permitting the delivering of melted gold from said crucible to said casting investment.

5. In a device of the class described, a housing member; a casting investment in said housing member provided with a cavity therein; a movably mounted crucible in said housing member provided with an inclined floor member and operatively positioned relative to said casting investment to move to a gold discharging position as respects said casting investment; crucible mounting means movably mounting said crucible to provide two gold melting and retaining positions and a gold discharging position, a first gold melting and retaining position in which gold to be melted is supported on a higher portion of said inclined floor member, a second gold melting and retaining position into which the crucible is moved by the flowing of melted gold down said inclined floor member, and a gold discharging position in which gold may be discharged into said casting investment; and crucible gold discharging means controlled by the movement of said crucible to its said second gold melting and retaining position for delivering melted gold from said crucible to said casting investment, said means comprising gas pressure discharging means urging the melted gold into the cavity within the casting investment.

6. In a device of the class described, a housing member provided with a crucible receiving chamber and with an opening for the inserting and removing of a crucible therethrough; a casting investment in said housing member; a crucible removably and movably mounted in said crucible receiving chamber and provided with an inclined floor member and operatively positioned relative to said casting investment to move to a gold discharging position as respects said casting investment; crucible mounting means movably mounting said crucible to provide two gold melting and retaining positions and a gold discharging position, a first gold melting and retaining position in which gold to be melted is supported on a higher portion of said inclined floor member, a second gold melting and retaining position into which the crucible is moved by the flowing of melted gold down said inclined floor member, and a gold discharging position in which gold may be discharged into said casting investment; and crucible gold discharging means controlled by the movement of said crucible to its said second gold melting and retaining position for delivering melted gold from said crucible to said casting investment.

7. In a device of the class described, a housing member; a casting investment in said housing member; a movably mounted crucible in said housing member provided with an inclined floor member and operatively positioned relative to said casting investment; and crucible gold discharging position as respects said casting investment; crucible mounting means movably mounting said crucible to provide two gold melting and retaining positions and a gold discharging position, a first gold melting and retaining position in which gold to be melted is supported on a higher portion of said inclined floor member, a second gold melting and retaining position

into which the crucible is moved by the flowing of melted gold down said inclined floor member, and a gold discharging position in which gold may be discharged into said casting investment; 5 electric switch means; means operatively connecting said switch means with said crucible for operating said switch means as the crucible is

removed to its said second gold melting and retaining position; and crucible gold discharging means controlled by said electrical switch means for delivering melted gold from said crucible to said casting investment. 5

GEORGE A. YANTIS.
